FRINGE CUTTING MACHINE

William A. Roberts, Paterson, N. J., assignor of
one-half to Thomas W. Roberts, Paterson,
N. J.

Application December 20, 1944, Serial No. 569,087

7 Claims. (Cl. 164—65)

My invention is a fringe-cutting machine.

An important object of the invention is to provide means for severing the fringe adjacent to the selvedge or longitudinal edge and adjacent to the intermediate portion of a continuous fabric strip while it is being fed longitudinally.

A further object of the invention is to provide means for holding the fringe taut during the severing action.

A further object of the invention is to center 10 the intermediate fringe with respect to the cutter, so that the fringes produced will be of the precise desired length.

A further object of the invention is to provide 15 a machine of the above-mentioned character which is rapid, automatic, and reliable in operation.

A further object of the invention is to provide 20 means for separating the severed selvedge or edge and the fringe-carrying fabric and winding the same in separate rolls.

A further object of the invention is to provide 25 means for moving the hooks for stretching the fringe and rendering the hooks adjustable for controlling their extent of movement.

Other objects and advantages of the invention 30 will be apparent during the course of the following description:

In the accompanying drawings forming a part 35 of this application, and in which like numerals are employed to designate like parts throughout same,

Figure 1 is a fragmentary plan view of a section 40 of fringe-carrying fabric, in connection with which my machine is used,

Figure 2 is a side elevation of the machine,

Figure 2a is a section taken on line 2a—2a of 45 Figure 2,

Figure 3 is a longitudinal section through the 50 fabric advancing and stretching device, parts broken away and parts omitted, showing the hooks in the inner position,

Figure 4 is a side elevation of the same, parts broken away,

Figure 5 is a longitudinal section through the 55 fabric advancing and stretching device, parts broken away and parts omitted, showing the hooks in the outer position,

Figure 6 is a side elevation of the same,

Figure 7 is a plan view of the fabric advancing 60 and stretching device,

Figure 8 is a transverse section taken on line 65 8—8 of Figure 7,

Figure 9 is a similar view, taken on line 9—9 70 of Figure 7,

Figure 10 is a similar view, taken on line 10—10,
Figure 11 is a longitudinal section taken on
line 11—11 of Figure 7,

Figure 12 is a horizontal section taken on line
5 12—12 of Figure 10.

In the drawings, wherein for the purpose of 10 illustration is shown a preferred embodiment of my invention, the numeral 10 designates uprights of a vertical frame having arms 11, provided with bearings 12, receiving a roller 13, having the fringe-carrying fabric 14 wound thereon. This fringe-carrying fabric is passed over an upper horizontal guide roller 15, rotatably mounted upon the tops of the uprights 10. The fabric also passes over a lower guide roller 16 and is wound upon a take-up roller 17.

The fabric 14 is woven and includes pairs of 15 transverse sections 18, connected by a transverse intermediate fringe 19, formed by the woof, with 20 the filling being omitted. At the outer ends of the sections 18, are fringes 20, formed by the filling and the omission of the woof, and these fringes are provided at their outer ends with a selvedge or edge 21, usually containing three woof 25 threads. Arranged between the inner ends of the sections 18 is an intermediate longitudinal fringe 22, formed by the filling and the omission of the woof threads. The fabric thus produced 30 is continuous and is wound upon the roller 13 and paid out from the same.

Arranged between the guide rollers 15 and 16 35 is a fabric advancing and stretching device 18'. This device comprises a horizontal transverse shaft 20', journaled in bearings formed upon uprights 21'. This shaft is free to rotate but cannot move longitudinally. The shaft 20' is 40 equipped with a pulley 22', receiving rotation from any suitable source. The fabric is preferably advanced about fifty yards per minute, although this rate of speed may be varied. Rigidly mounted upon the shaft 20' near its opposite ends are outer pairs of cylindrical discs 24. Each disc 24 is provided in its periphery with radial notches 25, which are preferably square in cross section. These notches are arranged suitably close together and their number may be varied. In each pair, the notches of one disc 24 are in 45 alignment with the notches of the other disc 24, and the aligned notches in one pair of discs are in alignment with the aligned notches in the other pair of discs. In connection with each pair of discs 24, the notches 25 receive reciprocatory carriers or rods 26, and the portions of these rods within the notches 25 are square in cross section so that the carriers or rods may move longi- 50 55

tudinally within the notches but cannot turn upon their longitudinal axes with relation to the discs 24. The rods 26 are held within the notches 25 by segments 27, arranged upon the faces of the discs 24 and secured thereto by screw 27' or the like. Each rod is urged outwardly by a compressible coil spring 28, as shown. At its inner end, each rod 26 is provided with an outwardly projecting radial hook 29. The fabric 14 passes from the roll 15 and travels about the inner ends of the annular group of carriers or rods 26, engaging the lower portion of these annular groups, usually corresponding to about one-fourth of the circumference of the annular groups. The outwardly projecting radial hooks 29 pass between the strands of the fringes 20 and are arranged between the fabric sections 18 and the selvedges 21. When the shaft 20' is continuously rotated at a selected speed, the annular groups of carriers or rods 26 and hooks 29 engaging with the fringe serve to feed or advance the fabric longitudinally.

The numeral 30 designates an intermediate pair of discs, rigidly mounted upon the shaft 20' and disposed adjacent to the intermediate fringe 22. The fabric sections 18 extend over the peripheries of the discs 30, Figure 3. These discs 30 are provided with radially projecting inclined fingers 31, converging outwardly. These fingers preferably correspond in number and arrangement to the carriers or rods 26. The fingers 31 pass between the strands of the intermediate fringes, and if the intermediate fringes were slightly off center with respect to the cutter, to be described, these fingers would accurately center the intermediate fringe. The discs 30 and fingers 31 also aid in feeding the fabric longitudinally.

Means are provided to control the reciprocatory movement of each annular set of rods 26. This means comprises a stationary cam disc 32, having an opening 33, through which the shaft 20' passes. The cam disc 32 is rigidly mounted upon a bracket 34 by means of bolts 34', and this bracket has a horizontal foot 35', provided with elongated slots 36', for receiving bolt 37' or the like for clamping the bracket 34 to the upright 10. The cam disc 32 and bracket 34 are therefore adjustable axially of the rotatable device 18' and its shaft 20'. The cam disc 32 constitutes an end thrust cam having a high face 34a and a low face 35. The lower face 35 extends for about one-fourth of the circumference of the cam disc 32, while the high face 34a extends for the remaining three-fourths of the circumference. There are inclined faces 36a at the ends of the low face 35, as shown. The stationary cam disc 32 is so mounted that the low face 35 is arranged to coincide with the lower portion of the annular group of carriers or rods 26, with which the fringes 20 engage. The rods 26 are urged outwardly by the springs 28, and this outward movement is prevented by the outer ends of the rods engaging the high face 34'. When each rod 26 travels from the high face 34' to the low face 35, its spring 28 moves it longitudinally outwardly, and this outward movement is limited by the rod engaging the low face 35. Each hook 29 passes between the strands of the fringe 20, and as each carrier or rod 26 is shifted outwardly, such hook 29 engages the selvedge or edge 21 and the fabric is pulled in the direction outwardly and longitudinally of the device 18', and the fringes 20 and 22 placed under tension. It is thus seen that as the sections 18 of the fabric pass beneath and

about the annular sets of carriers or rods 26, they are guided, supported, and advanced by these rods, which at the same time subject the fringes 20 and 22 to a longitudinal pull to hold them taut. When each rod 26 again travels upon the high face 34' of the cam disc, it is shifted inwardly so that the hook 29 is returned to the inner position, to occupy the proper relative position, to be again passed between the strands of the fringes 20, being advanced toward the same.

Means are provided to sever the fringes 20 and 22, comprising rotary cutters 37 and 38, mounted upon a horizontal transverse shaft 39, journaled in suitable bearings. This shaft receives rotation from a pulley 40 and the cutters are driven at a high speed, preferably about 2,500 R. P. M., although this speed may be varied. It is thus seen that each strand of the fringes 20 and 22 is brought into engagement with the rotary cutter, while the strand is held taut, and this permits the cutter to properly sever the strand. The rods 26, which hold the strands taut during the cutting step, remain in the outer position until the severing is completed, after which these rods move inwardly, as explained. The fringes 20 are severed as close to the selvedges or edges 21 as is practical, while the intermediate fringe 22 is severed at its true longitudinal center. As stated, the inclined fingers 31 center the intermediate fringe 22 with respect to the cutter 38, and this action is compensated for by the springs 28 of the rods 26, when these rods move outwardly. The centering of the intermediate fringe is ordinarily slight.

The continuous section of fabric is therefore severed into two longitudinal parts and two longitudinal selvedges. The longitudinal fabric parts are wound upon the roller 17, while the severed selvedges 21 are passed between a pair of rollers 39' and 40', the selvedge being preferably wound once around the upper roller. These rollers separate the selvedge from the fringe and may discharge the selvedge into a receptacle. It is preferred that the rollers 39' and 40' retain the selvedge between the roller 39' and the fringe slightly taut, so that there will be no liability of the selvedge being caught by the hooks. The roller 39' may be driven by any suitable means and it is preferred that it be driven by friction clutch means so that such driving means will slip if the tension on the selvedge becomes too great. The roller 17 may be driven by any suitable means to take up the fabric and there may be a slack in the fabric between the rollers 16 and 17.

The operation of the machine is as follows:

The fabric 14, woven as described, is wound upon the roller 13 and is paid out from the same. This fabric passes over the roll 15 and beneath and about the annular sets of carriers or rods 26 of the device 18', and then passes over the roller 16 and is wound upon the take-up roller 17. The outer fringes 20 have their ends connected by the selvedges 21, and these outer fringes engage and are supported, guided, and advanced by the annular sets of carriers or rods 26. The hooks 29 of the carriers or rods are passed between the strands of the fringes 20, when the carriers or rods 26 are in the inner position, and the carriers engage the high faces 34'. The continued turning of the discs 24 brings each rod 26 to the low face 35 and each rod then moves outwardly so that its hook 29 engages the selvedge 21. All of the rods 26 which are now engaging the low faces 35' have moved outwardly, and their hooks are

pulling outwardly axially of the device 18'. The fringes are thus held taut, and as each fringe is brought into engagement with the rotary cutter, it is severed. Shortly after the severing action, each rod or carrier 26 engages the high face 34' and is shifted inwardly so that its hook is positioned axially inwardly of the selvedge 21.

It is to be understood that the form of my invention herein shown and described is to be taken as a preferred example of the same, and that various changes in size, shape, and arrangement of parts, may be resorted to without departing from the spirit of my invention or the scope of the subjoined claims.

Having thus described my invention, I claim:

1. In a machine for manipulating a continuous fabric strip having outer fringes provided with selvedges, a support, payout means for the fabric mounted upon the support, guide means for the fabric mounted upon the support, a rotatable device mounted upon the support to engage and stretch the fabric, said rotatable device including outwardly projecting generally radial fingers to pass between the strands of the fringes inwardly of the selvedges, means to move the fingers outwardly toward the selvedges to hold the fringes taut, and means to sever the taut fringes.

2. In a machine for manipulating a continuous fabric strip having outer fringes provided with selvedges, a support, payout means for the fabric mounted upon the support, guide means for the fabric mounted upon the support, a rotatable device mounted upon the support to engage and stretch the fabric, said device comprising a rotatable support, carriers mounted upon the rotatable support to move axially with relation thereto, outwardly projecting generally radial fingers secured to the carriers to pass between the strands of the fringes inwardly of the selvedges, means to move the carriers axially outwardly to bring the fingers into engagement with the selvedges for holding the fringes taut and then move the fingers axially inwardly, and means to sever the fringes while held taut.

3. In a machine for manipulating a continuous fabric strip having outer fringes provided with selvedges and an intermediate fringe, a support, payout means for the fabric mounted upon the support, guide means for the fabric mounted upon the support, a rotatable device mounted upon the support to advance and stretch the fabric, said device including a rotatable support, carriers mounted upon the rotatable support to reciprocate axially of the rotatable support, outwardly projecting generally radial fingers mounted upon the carriers to pass between the strands of the outer fringes inwardly of the selvedges and to engage with the selvedges when the carriers are moved axially outwardly, means to reciprocate the carriers, and cutters arranged to sever the outer fringes and the intermediate fringe.

4. In a machine for manipulating a continuous fabric strip having outer fringes provided with selvedges and an intermediate fringe, a support, payout means for the fabric mounted upon the support, guide means for the fabric mounted upon the support, a rotatable device mounted upon

the support to advance the fabric and stretch the same, said rotatable device including a rotatable support, carriers mounted upon the rotatable support to reciprocate axially of the rotatable support, outwardly projecting generally radial fingers secured to the carriers to pass between the strands of the outer fringes inwardly of the selvedges, spring means to move the carriers axially outwardly, cams arranged to engage the outer ends of the carriers, and cutters arranged to sever the outer fringes and intermediate fringe.

5. In a machine for manipulating a continuous fabric strip having outer fringes provided with selvedges and an intermediate fringe, a support, payout means for the fabric mounted upon the support, guide means for the fabric mounted upon the support, a rotatable device mounted upon the support to engage the fabric, said rotatable device including a rotatable support, carriers mounted upon the rotatable support to reciprocate axially of the rotatable support, outwardly projecting generally radial fingers secured to the carriers to pass between the strands of the outer fringes inwardly of the selvedges, yielding means to move the carriers axially outwardly, end thrust cams arranged to engage the outer ends of the carriers, means to adjust the cams axially of the rotatable device and hold the same in the selected 30 adjusted position, and means to sever the fringes.

6. In a machine for manipulating a continuous fabric strip having outer fringes provided with selvedges and an intermediate fringe, a support, guide means for the fabric mounted upon the support, a rotatable device mounted upon the support for co-action with the fabric, said rotatable device including a rotatable support, outwardly projecting generally radial fingers mounted upon the rotatable support to pass between the strands of the outer fringes inwardly of the selvedges, means to move the fingers axially outwardly of the rotatable support into engagement with the selvedges, means mounted upon the rotatable support to pass between the strands of 40 the intermediate fringe and center the intermediate fringe, and cutters to sever the outer fringes and intermediate fringe.

7. In a machine for manipulating a continuous fabric strip having outer fringes provided with selvedges and an intermediate fringe, a rotatable device for co-action with the fabric, said rotatable device including a rotatable support, outwardly projecting generally radial fingers mounted upon the rotatable support to pass between the strands of the outer fringes inwardly of the selvedges, means to move the fingers axially outwardly of the rotatable support for engagement with the selvedges, sets of outwardly projecting fingers mounted upon the support and arranged 55 adjacent to the intermediate fringe, the sets of fingers converging radially outwardly and being adapted to be passed between the strands of the intermediate fringe to center the intermediate fringe, and means to sever the outer fringes and the intermediate fringe.
